Primary Examiner — George A Bugg

Assistant Examiner — Cole Sanders Holman

(57) **CLAIM**

The ornamental design for a 3D scanner as shown and described.

DESCRIPTION

1. 3D scanner
- 1.1 : Perspective
- 1.2 : Front
- 1.3 : Back
- 1.4 : Left
- 1.5 : Right
- 1.6 : Top
- 1.7 : Bottom
- 1.8 : Perspective
- 1.9 : Enlarged

FIG. 1.9 is an enlarged view of part 9 in FIG. 1.1; In the drawings, the broken lines are shown for the purpose of illustrating both parts of the article as well as boundaries of the claim; None of the broken lines form part of the claimed design.

1 Claim, 9 Drawing Sheets
